George Schubert.

UNITED STATES PATENT OFFICE.

GEORGE SCHUBERT, OF WALNUT, TEXAS.

GEAR-SHIFTING MECHANISM FOR HARVESTER-CONVEYERS.

SPECIFICATION forming part of Letters Patent No. 469,275, dated February 23, 1892.

Application filed February 27, 1891. Serial No. 383,082. (No model.)

To all whom it may concern:

Be it known that I, GEORGE SCHUBERT, a citizen of the United States, residing at Walnut, in the county of Bosque and State of Texas, have invented certain new and useful Improvements in Gear-Shifting Mechanism for Harvester-Conveyers; and I do hereby declare the following to be a full, clear, and exact description of the invention, such as will enable others skilled in the art to which it appertains to make and use the same.

This invention relates to improvements in gear-shifting mechanism for harvester-conveyers, and is especially adapted for the conveyer invented by myself and patented February 17, 1891, No. 446,473.

The object of my improvement is to provide a locking-lever by which the shifting-lever is shifted and locked in place after being shifted. I attain these objects by the mechanism illustrated in the accompanying drawings, in which—

Figure 1 is a plan view of part of a harvester provided with my improvement. Fig. 2 is a front view of part of Fig. 1, showing the shifting-gear in position. Fig. 3 is a sectional view taken on line 1 1, Fig. 1, looking in direction of arrow No. 1, showing parts beyond the section-line in full lines. Fig. 4 is a detail view of the shifting-lever as shown in Fig. 1, the locking-lever being shown in a locking position. Figs. 5 and 6 are detail views of the locking-lever. Figs. 7 and 8 are detail views of the shifting-lever, showing the locking-lever in dotted lines in position as when the conveyer is at rest; and Fig. 9 is a sectional view of the trunnioned step-bearing.

Similar letters refer to similar parts throughout the several views.

A designates the platform, which is formed of upper and lower floors or plates a and a' . The lower plate a is riveted to the lower flange of finger-bar and the upper plate is riveted to the upper face of the finger-bar B. Said plates a and a' are braced and secured to intervening strips b , b' , and b^2 , framed in the cross-sills d and d' , the rear strip b forming the rear sill of the platform, the strips b' and b^2 forming walls of the passage-way of the conveyer. Openings are made in the upper

plate a' for the purpose of the conveyer C and the devices carried by it.

B' designates a frame-bar secured to post D and finger-bar B and provided with a cross-bar D' near its inner or stubbleward end. To 55 said cross-bar D' are secured the posts D² and D³.

D⁴ designates a bar secured to post D and post D². To the rear of said bar, opposite the bevel-pinions e and e' , is secured the block E, 60 provided with a pin or stud f . To said stud is pivoted the shifting-lever F, secured thereto by a spring-pin f' .

D⁵ designates a bar secured to post D³, extending grainward and turned down at D⁶, 65 (see Fig. 2,) and then inward and secured to post D. To the part D⁶ of bar D⁵ is pivoted near its center the lever h, having its upper end slotted, so as to receive the shifting-rod j, and its lower end trimmed, so as to operate 70 in the slot g' on the front end of lever g. Said lever g is pivoted near its center to the under side of the plate a', as shown in Fig. 3. The rear end of said lever g extends into the passage-way of the conveyer and is operated by the latter.

g² is a rod connecting lever g with lever g³ for the purposes hereinafter described. The front end of lever g³ is pivoted to the platform, and its other end extends toward the 80 rear and into the passage-way of the conveyer.

J designates a shaft having its front end journaled in the trunnioned step-bearing I and its rear end journaled in the sill b, extending through the sills b' and b² and provided with a bevel-pinion J' near its front end, and a sprocket-wheel b⁴, located in the slot A' of the platform and provided with an endless chain b⁵, by which the conveyer is operated.

b⁶ is an idler, over which extends the chain b⁵ at the grain end of the platform. Said idler rotates on a shaft b⁷, secured in the strips b' and b², as seen in Fig. 1.

The lower end of a shaft J³ is journaled in the trunnioned bearing I and is provided with a bevel-pinion J² at its lower end, which is in constant mesh with bevel-pinion J'. The upper end of said shaft J³ is journaled 100

in the shifting-lever F, by which the upper end of said shaft is shifted into different positions.

5 e² is a bevel-pinion on the upper end of shaft J³, adapted to engage with bevel-pinion e or e'.

10 o designates a shaft having its bearing o' secured to the post D and its other bearing o² secured to the cross-bar o³. Said shaft is provided with a bevel-pinion e³ near its stubble-ward end, adapted to engage with any suitable driving mechanism of the harvester-gearing. (Not shown.) Bevel-pinions e and e' are secured to shaft o near the upper end of 15 the shaft J³ and a suitable distance apart, so that the bevel-pinion e² can be moved into engagement with bevel-pinion e or e' or out of engagement with either.

20 j designates a shifting-rod supported by the lug i' and the lever K'.

j' and j² are collars secured to shifting-rod j. Their positions on said rod are so located that when the gear is out of engagement the collars j² will rest against the lever K, while 25 the collar j' rests against the lug i'. The ends of the shifting-rod are threaded to receive the taps j³ and j⁴.

30 j⁵ is a spring coiled on a shifting-rod j between the lug i' and the washer h'. Said washer h' is loose on the rod j and rests against the lever h and is to prevent the spring j⁵ from engaging with the slot made in the upper end of the lever h.

35 P designates a downwardly-projecting stud secured to bar D⁵ in line with stud f. To its lower and downward projecting end is pivoted the locking-lever i at the point i². Said lever is constructed about as shown in Figs. 5 and 6. Its central arm i is perforated to receive the lug i', which has a partial rotation 40 therein. The lug i' is perforated so as to receive the shifting-rod j, by which the lever i is operated.

45 i³ and i⁴ are arms secured to the lever i in any suitable manner and provided with studs i⁵ and i⁶ at their ends, as shown, adapted to engage with the yoke or spanner cam-arms n² and n³, as shown, and for the purpose herein-after described.

50 F designates the shifting-lever, provided with a yoke or spanner formed by a cross-head on the outer end of the lever, the arms of which are bent outwardly to form right-angled offsets n and n', and from the ends of 55 which offsets outwardly-inclined cam-arms n² and n³ extend. The outer ends of the inclined cam-arms n² and n³ are curved toward each other to meet, as shown in Fig. 7, or approximately meet, as shown in Fig. 8, to form the 60 yoke.

I designates a trunnioned step-bearing having its rear trunnion I' mounted to turn in the upright flange of the frame-bar B' and drilled out to furnish a bearing for the front 65 end of the shaft J, with the forward trunnion journaled in the bracket I³ and having a down-

ward bearing I⁴ projecting, as shown thereby, for the vertical shaft J³, providing the same amount of side pressure from shaft J³ below the center of its trunnions, as above, thereby 70 overcoming the binding or side pressure on shaft J³.

In Fig. 4 the shifting-lever F is shown locked in one direction by the lever i in full lines and in the other direction in dotted 75 lines.

K designates a bracket secured to the bar D⁵ about the same distance from the stud P as the collars j' and j² are apart on rod j. To its upper end is secured the lever K', provided with a draw-rod K² at its upper end. Said draw-rod extends to the driver's seat (not shown in the drawings) and is operated by him. The lower end of said lever K' is somewhat flattened and curved outward and 80 perforated, as shown at K³ in Fig. 3, to secure the shifting-rod j, as described.

The operations are as follows: When enough grain has gathered on the platform, the driver draws the draw-rod K², thereby operating the lever K', moving the lower end K³ against the shoulder j² on shifting-rod j and shifting the latter in position, as seen in full lines, the collar j' shifting the lever i in position as seen in full lines, and it in turn shifts lever F and locks it in place, as seen in full lines in Fig. 1, thereby engaging bevel-pinion e² with bevel-pinion e, thus starting the conveyer. As the conveyer nears the forward end of its movement it strikes the lever 90 g and moves it along in position, as seen in dotted lines in Fig. 1. The lever g in turn moves lever h, as seen in dotted lines, the lever h first compressing the spring j⁵, and after the spring is compressed the levers will 95 act on the locking-lever i the same as a solid lever arrangement, forcing the stud i⁶ out of its locking position, when the stud i⁶ will come in contact with the arm n³, moving the shifting-lever over, thereby disengaging bevel-pinion e² from bevel-pinion e. The spring j⁵ 100 being compressed will move the shifting-lever F and locking-lever i in position, as seen in dotted lines in Fig. 1, and lock them in said position, thereby engaging bevel-pinion e² 105 with bevel-pinion e', which reverses the movement of the conveyer. The conveyer nears the end of its rearward movement it strikes the lever g³, moving it along, thereby moving lever g back, as seen in full lines, by means 110 of the connecting-rod g². The lever g in turn moves lever h, as seen in full lines, moving the upper end of lever h against the tap j³, drawing the lever i out of its locking position, when the stud i⁶ will shift the shifting-lever 115 F, and thus disengage bevel-pinion e² from bevel-pinion e', thus discontinuing the movement of the conveyer. The spring j⁵ will expand 120 sufficiently to prevent the engagement of bevel-pinion e² with bevel-pinion e until 125 shifted by the driver, as heretofore described.

Many slight changes can be made in the

locking-lever *i* and the shifting-lever *F* without a departure from the spirit or exceeding the scope of my invention. Hence I do not wish to restrict myself to the exact forms 5 herein shown; but,

Having fully described my invention, what I claim as new, and desire to secure by Letters Patent, is—

1. In a gear-shifting mechanism for har-
vesters, the combination, with a shifting-lever
F, pivoted at one end to the harvester-frame
and provided with a bearing *F'* and with
yoke cam-arms *n*² and *n*³, having offsets *n*
and *n'*, of a three-armed lever pivoted at its
15 rear to the harvester-frame and provided with
downwardly-projecting studs extending from
the outlet-arms of said lever, adapted to en-
gage with the yoke cam-arms, offsets to move
and lock said shifting-lever, constructed sub-
stantially as shown, a lug *i'*, pivoted to the
three-armed lever and perforated to receive
a shifting-rod *j*, and a lever *K'*, pivoted near
its center to the harvester-frame, with its lower
end perforated to receive the shifting-rod *j* and
25 provided with a draw-rod *K*² on its opposite
end, as shown, and for the purposes described.
2. In a gear-shifting mechanism for har-
vesters, the combination, with a shifting-lever
F, pivoted at one end to the harvester-frame

and provided with a bearing *F'* and with yoke 30
cam-arms *n*² and *n*³, having offsets *n* and *n'*,
of a three-armed lever pivoted at its rear to
the harvester-frame and provided with down-
wardly-projecting studs extending from the
outer arms of said lever, adapted to engage 35
with the yoke cam-arms, offsets to move
and lock said shifting-lever, constructed sub-
stantially as shown, a lug *i'*, pivoted to the
three-armed lever and perforated to receive
a shifting-rod *j*, a lever *h*, provided with a 40
slot to receive the shifting-rod *j*, a spring *j*⁵
on the shifting-rod *j*, the lever *h*, pivoted near
its center to the harvester-frame, a lever *g*,
pivoted in the platform, with its front end en-
gaging with the lever *h* and with its rear end 45
projecting in the passage-way of the con-
veyer, a bevel-pinion *J'* and a sprocketed wheel
*b*⁴ on a shaft *J*, a chain *b*⁵ to operate the con-
veyer *c*, bevel-pinions *J*² and *e*² on shaft *J*³,
bevel-pinions *e* and *e'* on a shaft *o*, and a trun-
nioned bearing, as shown, and for the pur- 50
poses described.

In testimony whereof I have affixed my signature in presence of two witnesses.

GEORGE SCHUBERT.
